ERNEST DICKEY, OF DAYTON, OHIO, ASSIGNOR TO DELCO-LIGHT COMPANY, OF DAYTON, OHIO, A CORPORATION OF DELAWARE.

ELECTRICAL APPARATUS.

Application filed December 18, 1922, Serial No. 607,488. Renewed September 7, 1927.

This invention relates to electrical systems wherein a dynamo driven by an internal-combustion engine provides current for lighting or power purposes and also for the 5 electrical ignition for the engine.

One object of the present invention is to provide a dynamo having a plurality of generating circuits, one circuit providing relatively high voltage, for example, 110 volts, 10 for a lighting or other work circuit, and another circuit of the dynamo providing a relatively low voltage, for example, 6 volts, for supplying current to the ignition apparatus of the engine which drives the dynamo.

15 A further object of the invention is to provide a dynamo-electric machine which may be driven by an internal-combustion engine and which will generate a relatively high voltage current for a work circuit, and a 20 relatively low voltage current to charge a storage battery and to provide ignition current for the engine, said dynamo being operable as a motor upon the delivery of current from the battery whereby the dynamo 25 may be used to crank the engine.

A further object of the invention is to provide automatic means which when manually set into operation will cause current to flow from the battery into the dynamo and into the ignition system in order that the 30 engine may be started, and which will, when the engine becomes self-operative, automatically cause a low voltage current to be delivered to the battery and to the ignition system while a high voltage generating circuit may be connected with a work circuit.

A further object is to provide manual means for discontinuing the operation of the engine and dynamo, and which will so act 40 upon the aforesaid automatic means that the circuits will be restored to inoperative condition and will be ready for the starting of the engine when desired.

Other and further objects and advantages 45 of the present invention will be apparent from the following description of a preferred embodiment thereof, reference being made to the accompanying drawing.

The figure of the drawing is a wiring diagram showing a preferred form of the invention.

In the drawing, an internal-combustion engine 20 having a crank 20^a, a shaft 21, and a flywheel 22 drives a dynamo 23. Dynamo

23 includes an armature core 24 carrying 55 two armature circuits. One of these armature circuits is arranged to generate a relatively high voltage, for example, 110 volts, and this circuit is connected with a commutator 25. This core 24 carries an armature 60 winding constructed to generate a relatively low voltage, for example, 6 volts, and this winding is connected with a commutator 26. The shunt field winding 27 cooperates with the 110 volt armature circuit, the series field 65 winding 28 cooperates with the 6 volt armature circuit, and 29 is a series winding for regulating purposes, this winding cooperating with the field winding 27 and tends to maintain a substantially constant generator 70 voltage over relatively wide range of current delivered to the work circuit. Brushes 30 and 31 cooperate with commutator 25, and brush 30 is connected with shunt field 27 which is connected by wire 34 with brush 31 75 and with series field 29, wires 35 and 36 connect respectively a brush 30 and the series field 29 with a double pole switch 37 leading to a work circuit which includes main leads 38 and 39.

80 The automatic controlling means designated as a whole by numeral 40 includes a magnet winding 41 which, when energized, will attract a contact 42 against the action of springs 43 into engagement with contacts 44 and 45. There are also two magnet windings 46 and 47, the former when energized causing the contact 48 to move into engagement with contacts 49 and 50 against the action of a spring 51, and the latter when 85 energized will overcome the magnetism produced by the magnet 46 and the contact 48 will be retracted by the spring 51. The contact 49 is connected by wire 52 with brush 33. The winding 46 is connected by wire 95 53 with wire 35 and by wire 54 with wire 34. Contacts 50 and 44 are connected with wire 55, and these contacts are connected by wire 56 with a 6 volt battery, for example, 57 which in turn is connected by wire 58 100 with wire 35 and by wire 59 with brush 32. The contacts 48 and 42 are connected together by wire 60, and these contacts are connected by wire 61 with the primary circuit of the engine ignition system which includes 105 timer 62 and ignition coil primary 63 which is connected by wire 64 with battery 57. The ignition coil secondary 65 is grounded at 66

and connects to a spark plug 67 attached to an engine cylinder. The manually operable controlling means designated as a whole by number 70, includes a stationary contact 71 connected by wire 72 with wire 35, a contact 73 movable against the action of a spring 74 into engagement with contact 71 and contact 75 movable against the action of a spring 76 into engagement with contact 71. Contact 75 is connected by wire 77 to winding 47 and contact 73 is connected by wire 78 to magnet winding 41.

The operation of the invention is as follows: To start the plant a contact 73 is moved into engagement with contact 71 thereby causing current to flow from the battery through the relay magnet 41 through the following circuit: Battery 57, wire 56, wire 55, contact 44, relay winding 41, wire 78, contacts 73, 71, wire 72, wire 35, wire 58. The contact 42 will be moved into engagement with the contacts 44 and 45 and the following ignition circuit will be established: Battery 57, wire 56, wire 55, contact 44, contact 42, wire 60, wire 61, timer 62, ignition coil primary 63, wire 64. The following cranking circuit will be established at the same time: Battery 57 wire 56, wire 55, contacts 44, 42, 45, wire 80, low voltage series field 28, brush 33, low voltage armature circuit connected with commutator 26, brush 32, wire 59, wire 58.

After the engine has become self-operative the dynamo 23 will operate as a generator and the automatic device 40 will be so controlled by the functioning of the dynamo 23 as a generator that the manually controlled contact 73 may be released. This function of the automatic device 40 is as follows: The magnet winding 46 will be energized through the following high voltage circuit: armature circuit connected with commutator 25, brush 31, wire 34, wire 54, magnet 46, wire 53, wire 35, brush 30, the work circuit not being connected, the exciting field circuit will include the winding 27 which is connected between the brushes 30 and 31. The winding 46 being energized, the contact 48 will be drawn into engagement with the contacts 49 and 50 and the following circuits will be established between the low voltage armature circuit and the battery and the engine ignition apparatus. The battery charging circuit is as follows: Low voltage armature circuit connected with commutator 26, brush 33, wire 52, contacts 49, 48, 50, wire 55, wire 56, battery 57, wire 58, wire 59, brush 32. The ignition circuit is as follows: Commutator 26, brush 33, wire 52, contacts 49, 48, wire 60, wire 61, timer 62, ignition coil primary 63, wire 64, wire 58, wire 59, brush 32. Since these circuits are maintained while the coil 46 is energized then the operator may release the contact 73 and the spring 74 will pull 73 out of engagement with 71. Thereupon circuit

connections with the magnet 41 will be broken and the contact 42 will be drawn by the spring 43 into the position shown.

While the low voltage armature circuit may be supplying the battery and ignition apparatus, the higher voltage armature may be supplying the work circuit leads 38 and 39, the main switch 37 being closed. In order to compensate for voltage drop across the armature lead due to an increase in current consumed by the work circuit the dynamo is provided with the compensating cumulative series field winding 29.

To stop the plant the contact 75 is pushed into engagement with the contact 71 and the magnet winding 47 will be energized through the following circuit: Commutator 26, brush 33, wire 52, contacts 48, 49, 50, magnet 47, wire 77, contacts 75, 71, wire 72, wire 35, wire 59, brush 32. The windings of the magnet 47 are so constructed that when energized by current by the 6 volt potential enough magnetism will be generated of opposite polarity of that generated by the winding 46 so that the fluxes 82 and 83 produced respectively by these windings and represented by arrows pointing in opposite direction in the drawings will substantially balance each other. Thereupon the contact 48 will be drawn out of engagement with contacts 49 and 50 by means of the spring 51 whereupon the engine will stop for lack of ignition.

It is to be understood that any number of the manual operable controllers 70 can be provided for example, a control 70 can be provided on each floor of a house and one in each out building or if desirable one can be provided for each service switch. It will be noted that the plant can be stopped by any of the plurality of contacts 75 regardless at which controller 70 the plant was started; or the plant can be started at any controller 70 regardless at which controller the plant was stopped. In this manner it is unnecessary to return to that particular controller at which the last controlling operation was performed, to again control the plant.

A voltage control 85 comprising a solenoid core 86 and a coil 87 is provided, one of said coil leads being connected by wires 58 and 35 to brush 30 and the other lead by wire 34 to brush 31. The solenoid core when actuated by the coil 87 will control a valve 88 located in the engine intake 89. Voltage control 85 is adapted to control the speed of the engine and thereby the output of the generator in order to maintain the voltage of the generator substantially constant under varying load conditions.

It is apparent from the foregoing description that there has been provided an electrical power plant from which current may be taken directly to operate motors or lamps

or other translation devices and from which current at a relatively low voltage may be taken to charge a storage battery and to supply ignition current for the engine. This 5 battery is not used to supply the work circuit but is of sufficient capacity to operate the dynamo of the power plant as a motor for cranking the engine and at the same time to supply current for ignition during the 10 cranking operation. This sort of generating system is particularly useful where current for power and lighting purposes need not be continuously available and where the engine of the power plant can be set into operation 15 whenever current or power is needed. Therefore the storage battery is no larger than necessary to supply the starting ignition current and the cranking current.

Another important advantage of the invention 20 is in the automatic device which by a single manual operation sets up the starting ignition and engine cranking circuits; and sets up the battery charging circuit, the 25 engine running ignition circuit after the engine has become self-operative. There is but one other manually controllable device and this is used in stopping the plant.

While the form of mechanism herein 30 shown and described constitutes a preferred embodiment of one form of the invention, it is to be understood that other forms might be adopted and various changes and alterations made in the shape, size, and proportion of the elements therein without departing 35 from the spirit and scope of the invention.

What is claimed is as follows:

1. In an electrical generating system, the 40 combination with a dynamo and an internal combustion engine, said dynamo having relatively high resistance shunt and low resistance series field windings, and having a relatively high voltage armature cooperating with the shunt field winding for supplying current to a work circuit, and having a relatively low voltage armature cooperating with the series field winding whereby the dynamo may be operated as a motor to crank the engine, said low voltage armature being 45 adapted to cooperate with the shunt field winding to generate a current for battery charging; of a storage battery; of means for connecting the storage battery with the low voltage armature and series field for rendering the dynamo operable as a motor; and means for rendering the series field winding inoperative during the generating operation.

2. In an electrical generating system, the 50 combination with a dynamo and an internal combustion engine, said dynamo having relatively high resistance shunt and low resistance series field windings, and having a relatively high voltage armature cooperating 55 with the shunt field winding for supply-

ing current to a work circuit, and having a 65 relatively low voltage armature cooperating with the series field winding whereby the dynamo may be operated as a motor to crank the engine, said low voltage armature being adapted to cooperate with the shunt 70 field winding to generate a current for battery charging; of a storage battery; of means for connecting the storage battery with the low voltage armature and series field for rendering the dynamo operable as 75 a motor; and means dependent upon the operation of the engine for rendering the series field inoperative, and for connecting the low voltage armature in battery charging 80 relation with the battery.

3. In an electrical generating system, the combination with a dynamo and an internal combustion engine, said dynamo having relatively high resistance shunt and low resistance series field windings, and having a 85 relatively high voltage armature cooperating with the shunt field winding for supplying current to a work circuit, and having a relatively low voltage armature cooperating with the series field winding whereby 90 the dynamo may be operated as a motor to crank the engine, said low voltage armature being adapted to cooperate with the shunt field winding to generate a current for battery charging; of a storage battery; of 95 means for connecting the storage battery with the low voltage armature and series field for rendering the dynamo operable as a motor; a switch for rendering the series field inoperative and for connecting the low 100 voltage armature in battery charging relation with the battery; a magnetic coil responsive to the voltage across the high voltage armature for actuating said switch; a second magnetic coil cooperating with said 105 switch for rendering the engine inoperative; and means for rendering said second coil operative.

4. In an electrical generating system, the combination with a dynamo and an internal 110 combustion engine, said dynamo having relatively high resistance shunt and low resistance series field windings, and having a relatively high voltage armature cooperating with the shunt field winding for supplying current to a work circuit, and having a relatively low voltage armature cooperating with the series field winding whereby 115 the dynamo may be operated as a motor to crank the engine, said low voltage 120 armature being adapted to cooperate with the shunt field winding to generate a current for battery charging; of a storage battery; of means for connecting the storage battery with the low voltage armature and series field for rendering the dynamo operable as a motor; a switch for rendering the 125 series field inoperative and for connecting

the low voltage armature in battery charging relation with the battery; a magnetic coil responsive to the voltage across the high voltage armature for actuating said switch; 5 a second magnetic coil adapted to magnetically oppose the first coil; and means for rendering said second coil operative.

5. In an electrical generating system, the combination with an internal combustion 10 engine and a dynamo-electric machine having relatively high and relatively low voltage armature winding, said dynamo having a field winding for exciting the machine while generating and having a field winding 15 for exciting the machine while motoring; of a storage battery; means for connecting the battery with the second named field winding and the low voltage armature winding to operate the dynamo as a motor 20 for engine starting; and means for rendering said second field winding ineffective during generating operation and for connecting

the low voltage armature winding with the battery for charging purposes.

6. In an electrical generating system, the combination with an internal combustion engine and a dynamo-electric machine having relatively high and relatively low voltage armature winding, said dynamo having a field winding for exciting the machine while generating, and having a field winding for exciting the machine while motoring; of a storage battery of substantially the same voltage as the relatively low voltage armature winding; means for connecting the battery with the second named field winding and the low voltage armature winding to operate the dynamo as a motor for engine starting, and means for connecting the low voltage armature winding with the battery 40 for charging purposes.

In testimony whereof I hereto affix my signature.

ERNEST DICKEY.
